MICHAEL G. WASCHKO, OF HAZLETON, PENNSYLVANIA.

HAIRPIN.

1,315,926.

Specification of Letters Patent.

Patented Sept. 9, 1919.

Application filed September 22, 1917. Serial No. 192,739.

To all whom it may concern:

Be it known that I, GEORGE C. GASPER, Jr., a citizen of the United States, residing at 625 N. Wyoming St., Hazleton, in the 5 county of Luzerne and State of Pennsylvania, have invented new and useful Improvements in Hairpins, of which the following is a specification.

This invention relates to new and useful 10 improvements in hairpins, and has for an object to provide a hairpin which will more effectively support and retain the hair in adjusted positions than will the hairpins of common usage, by having novel features of 15 construction embodied therein capable of preventing the hair from becoming accidentally disarranged or disengaged from the hair while associated with the latter.

To this end, the invention comprises, 20 among other features, a hairpin formed from a single piece of bent wire or similar material, the same being folded or doubled in the usual manner to provide a looped upper extremity and downwardly extending 25 legs or tines, an offset locking portion being formed in the pin to connect the looped extremity with the legs or tines, said offset portion being located at right angles to the aforesaid parts of the hairpin, in order to 30 provide a shoulder, which is adapted to be embedded in and caught by the hair in such a manner as to prevent undue movement of the pin, yet to permit of its convenient removal when manipulated in a required manner.

For a further disclosure of the invention, reference is to be had to the following description and to the accompanying drawing, forming a part of the specification, and in 40 which—

Figure 1 is a perspective view of the preferred form of the hairpin comprising the present invention, and

Fig. 2 is an end elevation thereof, illustrating the pin in a locked position in the hair, and disclosing by dotted lines the movement required to effect its removal.

Similar characters of reference denote corresponding parts throughout the several 50 views of the drawing.

The hairpin 1, comprising the preferred form of the invention is formed from a single piece of bent wire, or any other suitable material, and is adapted to be doubled 55 in its length to provide the usual looped ex-

tremity 2 at its upper end, and spaced vertically extending legs or tines 3. The lower ends of the latter are separated, as usual, to permit the pin to be readily inserted into engagement with the hair. As is 60 well known, considerable difficulty has been encountered in retaining the common form of hairpin in a fixed and adjusted position within the hair, and it is to overcome this objection, and others, that has lead to the 65 development of the pin 1.

To this end, the upper extremities of the tines 3 are sharply bent at right angles to their general plane so as to provide spaced locking shoulders 4, whereby an accentuated 70 and well-defined offset will be formed in the body of the pin, as will be seen upon reference to Fig. 2 of the drawing. The shoulders 4 inwardly terminate in the upwardly 75 bent, looped, manipulating extremity 2, which is also disposed at right angles to the shoulders 4, but is situated on a vertical plane offset from that of the tines 3.

In operation, when the pin 1 is inserted 80 into the hair, the shoulders 4 will be securely embedded in the latter, so that strands of hair 5 will overlap the same, therefore preventing undue movement of the pin, when the same is thus situated. It will be apparent that the locking means provided will 85 effectively prevent the pin from becoming accidentally disarranged or lost. The fact that the shoulders 4 are arranged at right angles to the extremity 2 and to the tines 3, permits of this advantage, for if the shoulders 90 4 were bent at other than right angles, the hairpin would have a tendency to work loose. When it is desired to remove the pin from an operative position, the extremity 2 is grasped, in the manner shown 95 in Fig. 2, and is slightly rocked so that the strands of hair 5 will be freed from engagement with the shoulders, thus permitting the pin to be conveniently withdrawn 100 by a simple movement, and without incurring discomfort to the wearer.

I am aware that structures have been previously developed wherein the tines of a hairpin are offset from the looped manipulating extremities thereof, therefore, I do 105 not claim this principle broadly, but what is claimed as new and patentable is:

A hairpin constructed from a single length of wire, and including a looped extremity and parallel limbs equidistantly 110

spaced throughout their length, each of said limbs at a point adjacent the closed end of the pin, being formed to provide a locking shoulder, said locking shoulders extending a common direction and disposed at a right angle with respect to the limbs of the pin, said locking shoulders also being equi-

distantly spaced, and said looped extremity through the instrumentality of said locking shoulders being disposed to lie in a plane in spaced parallel relation to the limbs of the pin.

In testimony whereof I affix my signature.
GEORGE C. GASPER, JR.
